(57) **CLAIM**

The ornamental design for a vehicle taillight as shown and described.

DESCRIPTION

FIG. 1 is a front view of the vehicle taillight showing the present design;

FIG. 2 is a left side view thereof, the right side being a mirror image;

FIG. 3 is a front, top and left side perspective view thereof; and,

FIG. 4 is a front and left side perspective view thereof. The features shown in broken lines form no part of the claimed design.
